UNITED STATES PATENT OFFICE.

DAVID H. BEELMAN, OF PITTSBURGH, PENNSYLVANIA.

VENDING MACHINE.

Original application filed July 23, 1923, Serial No. 653,087. Divided and this application filed November 9, 1925. Serial No. 67,779.

My invention is an improvement in vending machines, and relates more especially to that particular type in which the articles to be dispensed are stacked in a compartment 5 and discharged from the lower end of the stack upon the operation of mechanism released by the insertion of a coin.

This application is a division of my pending application for patent filed July 23, 1923, Serial No. 653,087, and the subject-matter herein claimed refers particularly to the coin controlled mechanism for releasing the article-discharging mechanism.

The principal object of that part of my 15 invention claimed herein is to provide a coin-controlled mechanism, simple in construction and positive in action, which will securely lock the operating shaft of the article-discharging mechanism against movement and is actuated by the weight of a coin to automatically release the shaft; said coin-controlled mechanism in the present instance being employed in connection with article-discharging mechanism of particular 20 construction including a pawl and ratchet device acting on the shaft to require a full stroke of the operating lever in either direction before permitting of a return movement thereof, all as hereinafter fully described in the complete disclosure of my improved vending machine.

In the accompanying drawings:

Figure 1 is a front elevation of a vending machine embodying my invention.

Fig. 2 is a side view of the same with the lower end of the casing broken away to show the coin-controlled and article-discharging mechanisms.

Fig. 3 is a vertical sectional view on the 40 line 3—3 of Fig. 2.

Fig. 4 is a side elevation of the coin-controlled mechanism for normally locking the operating shaft of the article-discharging mechanism, the parts being shown in locked 45 position.

Fig. 5 is a similar view, showing the mechanism released by a coin.

Fig. 6 is a side view of the plate or casting 50 on which the coin-controlled mechanism is mounted.

Fig. 7 is a horizontal sectional view on the line 7—7 of Fig. 4.

Figs. 8 and 9 are side and edge views, respectively, of the pivoted dog forming part of the releasing mechanism. 55

Fig. 10 is a side elevation showing the connected sprocket and ratchet wheels of the article-discharging mechanism.

Fig. 11 is an elevation of the pawl and ratchet device acting on the operating-shaft 60 to compel a full lever-stroke in either direction.

Fig. 12 is a detail front elevation of the article-discharging mechanism including the pawl and ratchet device cooperating therewith. 65

In carrying out my invention the casing of the vending machine is of a conventional shape with a main or body portion 10 and forwardly-projecting lower extension 11, the upper part of the body portion being divided by a partition 12 to provide separate compartments for the articles to be vended while the lower part is separated by the bottom 13 for the compartments and contains the mechanisms hereinafter described, being protected from the articles discharged by an inclined plate 14 continued from the bottom-plate 13 and terminating slightly in the rear of an opening 15 through which the articles 70 are removed from the machine. Between each side wall of the casing and adjoining side wall, as 16, of the compartment for the articles there is a space to receive a coin-chute 17 entrance to which is by way of the 75 coin-slot 18 in the front of the casing, each coin-chute terminating above and in line with its companion coin-controlled mechanism as shown in Fig. 3.

As the coin-controlled mechanism, article-discharging mechanism, and pawl and ratchet device are duplicated with respect to each compartment so that the latter may contain different articles which may be vended independently a description of the 95 set of mechanism for one compartment will apply also to the other, like numerals of reference being used.

The articles A are stacked in the compartment upon the bottom 13 and are discharged down the inclined plate 14 one at a time by means of pushers 19 on an endless sprocket-chain 20 driven by a sprocket-wheel 21 loosely mounted on the main shaft 22

supported at one end by a side wall of the casing and at the other end by a vertical standard 23, said sprocket-wheel being turned by a pawl and ratchet-wheel. The ratchet-wheel 24, is secured to one side of the sprocket-wheel and freely turns on the shaft therewith while the pawl, 25, is pivoted to the outer end of an arm 26 fixed to the shaft by means of a hub 27 (Fig. 12), whereby said pawl and ratchet-wheel mechanism will be actuated to turn the sprocket-wheel on operation of the lever 28 secured to the outer end of the shaft beyond one side of the casing; it being noted by reference to Fig. 3 that a separate shaft is employed for the sprocket-wheel, &c., below each article-compartment. Backward movement of the combined sprocket and ratchet wheel is prevented by means of a spring catch or pawl 29 secured to and projecting downwardly from the underside of the bottom plate 13. It will be noted that the lower portion only of the endless sprocket-chain 20 is engaged by the sprocket-wheel 21 and that the upper portion of said chain passes over a depressed portion 30 of the bottom-plate 13, said depressed portion practically providing a channel for the passage of the sprocket-chain below the stack of articles at the center thereof and that the pushers 19 project outwardly from the sprocket-chain only a sufficient distance to engage the lowermost article of the stack as the chain travels along said channel. To properly guide that portion of the sprocket-chain removed from the sprocket-wheel to and from the aforesaid channel there are idle-wheels 31 and 32, wheel 32 being preferably provided with teeth (as shown) and supported in a bracket 33 rising from the bottom of the casing while wheel 31 is in the form of an ordinary plain roller. The rear wall 34 of the article-compartment is slightly in advance of the rear end of the upper horizontal stretch of the sprocket-chain, or in front of the idle-roller 31, and the lower end of this wall is provided with an opening 35 through which the pushers 19 pass to the channel, and to align the forward end of the stack of articles, as books or pamphlets A, slightly in front of the forward end of said horizontal stretch of sprocket-chain there is a vertical plate 36 spaced from the front wall of the casing by brackets 37. Furthermore, to prevent articles from being extracted from the machine by passing a wire up through the discharge opening 15 a swinging door 38 is located above the upper portion of the inclined plate 14 with its lower end resting thereagainst, the door swinging outwardly for the passage of an article by the same.

As hereinbefore explained the combined sprocket-wheel and ratchet-wheel are loosely mounted on the operating shaft 22 and are turned by the pawl 25 at the outer end of

the arm 26 fixed to said shaft, and of course the lever 28 operating the shaft and arm is limited in its movement to turn the sprocket-wheel the required distance to move the sprocket-chain a sufficient distance to discharge an article by the pushers 19—a plurality of the latter being used and spaced accordingly. Now in order to compel full stroke of the operating lever in both directions after release of the operating shaft by the coin-controlled mechanism hereinafter described, and thereby prevent a manipulation of said lever (as by partial movement of the same back and forth) to discharge more than one article upon the insertion of a single coin, I provide an auxiliary pawl and ratchet device more clearly illustrated in Figs. 11 and 12. For this purpose a ratchet-wheel 39 is fixed on the shaft 22 to turn therewith, being preferably formed integral with the hub 27 of the operating arm 26 carrying pawl 25 and located at one side of a bracket 40 depending from the bottom-plate 13, and as said ratchet-wheel has a limited oscillating-rotary movement, corresponding with the movement of the operating-lever 28, a segmental portion thereof is provided with teeth and the other portion extended to form a downwardly and forwardly projecting arm 39a actuated by a spring 41 serving to return said ratchet-wheel and shaft to normal position. Adapted to engage this ratchet-wheel alternately are pawls 42 and 43 pivoted to the bracket 40 above the ratchet-wheel and actuated towards each other in engagement with said ratchet-wheel by a coiled spring 44 connecting them. For moving one of the pawls away from the ratchet-wheel while the other is in engagement therewith, and vice versa, I provide a tappet 45 which is pivoted between said pawls to the bracket 40 and has a depending tail-piece 45a the lower end of which is in the path of spaced apart pins 46 46 projecting from the face of the ratchet-wheel, the ends of the upper portion or cross-head of the tappet working in recesses at the inner sides of the pawls and against inclined surfaces formed by said recesses; that is to say, when the tappet is rocked or positioned so that one end of its cross-head is in the deeper part of the recess in one of the pawls that pawl will be in engagement with the ratchet-wheel and the other end of said cross-piece will be in engagement with the inclined surface of the recess in the other pawl to hold said pawl out of engagement with the ratchet-wheel, and vice versa when the tappet is rocked in the other direction, it being understood of course that the pins 46 are spaced to correspond with the full movement of the operating lever 28 and shaft 22. In Fig. 11 the parts of this ratchet and pawl device are shown in the position they assume when the mechanism of

the vending machine is in normal position for operation by the insertion of a coin, and when the shaft is turned in the direction of the arrow pawl 42 will travel over the teeth 5 and prevent backward movement, thereby compelling a full stroke, and in like manner pawl 43 will operate to compel a full return stroke inasmuch as the pins 46 on the ratchet-wheel shift the tappet at the end of each 10 stroke of the lever. This arrangement not only prevents the operating lever and shaft from being operated by short intermediate strokes back and forth but being held against backward movement it protects the 15 purchaser or operator, as for instance should the operator inadvertently release the lever before completing a full stroke it will be held to position to permit the stroke to be completed. A continuous return stroke of 20 the lever is also assured, either by manipulation of said lever or by the spring 41.

The mechanism hereinbefore specifically described forms the subject-matter of the claims of my application referred to and is 25 shown and described herein for a complete disclosure of my invention, inasmuch as said mechanism or mechanisms effectively cooperate with my improved coin-controlled mechanism which I will now fully describe.

30 The coin-controlled mechanism is mounted on a supporting plate or casting 50 disposed vertically in the lower part of the casing 10 alongside of the combined sprocket-wheel and ratchet-wheel with the main operating shaft 22 passing through the lower part of a thickened body portion 50^a of said plate and the coin-chute 17 terminating on a line with and above a vertical passageway 51 into which the coin drops for the operation of this 35 mechanism. The formation of the supporting plate or casting is clearly shown in Fig. 6, from which it will be seen that the mechanism is attached to the body portion 50^a and that the front wall of the passageway 51 through which the coin 52 passes is provided with an arc-shaped pocket 51^a co-operating with a pivoted dog 53 forming part of the locking mechanism, the passageway extending from the upper end of the body portion—where the coin enters—to the lower end thereof—where the coin is discharged,—and is of sufficient width to receive the coin and pivoted dog (Fig. 5) 40 with the rear wall of said passageway curved 45 in the arc of a circle for the operation of the dog as hereinafter described. There is a curved slot 54 in the front wall of the passageway beginning at the upper front end of the body portion of the supporting plate and terminating near the lower end thereof where it is contracted to form a notch 55, the slot and passageway providing an inwardly-projecting wall 56 having an inner 50 edge 56^a curved in the segment of a circle 55 while the rear edge of the slot and rear wall

of the passageway coincide for a greater portion of the length of the passageway or to near the discharge end thereof.

The operating shaft 22 through the body portion of the supporting plate at the lower end thereof in the rear of the curved slot 54, and at the forward end of said body portion, on a horizontal line with the shaft 22, there is a stub-shaft 57 carrying levers 58 and 59 at opposite sides of the supporting-plate and between the upper ends of which the dog 53 is pivoted to suspend therefrom in the passageway 51, the levers extending below the stub-shaft and body portion of the supporting-plate for the connection thereto of a link 60 extending from an operating-arm 61 secured to the shaft 22 for the operation of the levers by said shaft. The pin 58^a connecting the upper ends of the levers 58 and 59, and on which the dog 53 is pivoted, works in a curved slot 70 in the supporting-plate. The lever 58 provides the means for locking the operating-shaft 22 against movement and for this purpose the upper end thereof is engaged by a catch 62 pivoted at 63 and having a forwardly projecting tail-piece or member 62^a engaged by the forward end of a horizontal trip-lever 64, the latter being operated by the swinging-dog 53 in the manner hereinafter described. A flat spring 65 bears lightly on the catch and a helical spring 66 exerts a light tension on the tripping-lever being connected to the rearwardly-projecting end thereof. The dog 53 which works in the passageway and receives the coin 52 between it and the pocket 51^a has a rib 53^a projecting through the curved slot 54, with the forward edge of said rib corresponding in shape with the curved edge 56^a and the rear edge presenting a curved surface 53^b engaging the trip-lever 64, the lower end of the rib being rounded to engage in the notch 55 when the parts are in normal position 50 to be operated by a coin. The lower edge of the rearwardly projecting portion of the rib providing the lever engaging surface 53^b is curved and the lower part of the rear edge curved in an opposite direction from said lever engaging surface so as to ride over the inner end of the yielding spring-actuated trip-lever on the return or backward movement of the upper end of the lever 58 carrying said dog.

55 The normal position of the cooperating parts of the coin-controlled mechanism is illustrated in Fig. 4 of the drawings, the lever 58 being locked by the catch 62 to prevent movement of the shaft 22 which operates sprocket-wheel 21 of the article-discharging mechanism with the suspended dog 53 in engagement with the curved wall 56 and notch 55 for swinging movement rearward by the weight of the coin as it passes 60 into the pocket 51^a, when the parts will as-

sume the position shown in Fig. 5, from which it will be understood that as the dog swings rearward the rib thereon raises the forward end of the trip-lever which actuates the catch to release the locking-lever 58 for the operation of the article-discharging mechanism by a forward movement of the operating-lever 28 attached to the operating-shaft 22. This operation of the shaft not only turns the sprocket-wheel and sprocket-chain a predetermined distance through the intervention of the ratchet-wheel 24 and pawl 25 for discharging an article from the bottom of the stack by one of the pushers 19 on the sprocket-chain but also operates the auxiliary ratchet-wheel 39 to change position of the pawls 42 and 43 acting on said ratchet-wheel for preventing backward movement of the shaft. After an article has been discharged down the incline 14 from the compartment by a complete forward stroke of the operating lever 28 the parts of the coin-controlled mechanism and operating-shaft may be returned to normal position either by manipulation of said operating-lever or automatically by the action of spring 41 pulling on the arm 39^a attached to and projecting from the shaft 22, in either instance the pawl 43 now engaging the ratchet-wheel 39 to prevent backward movement. From the foregoing description it will be readily seen that the coin-controlled mechanism will positively lock the shaft from operation by the hand-lever 28 until a coin is dropped into the chute and passes into the pocket 51^a to operate said mechanism for releasing the shaft, and that it absolutely insures a complete operation for the discharge of an article before the coin is discharged by reason of the cooperation therewith of the pawl and ratchet device inasmuch as when the coin releases the locking mechanism a movement of the locking-lever and dog a sufficient distance to discharge the coin out of the pocket past the lower end of the dog will position the upper catch-end of said locking-lever beyond the end of the catch, and pawl 42 of the cooperating pawl and ratchet device being in engagement with the ratchet-wheel 39 will prevent the locking-lever 58 being returned to normal position until the forward stroke thereof—corresponding to the full forward stroke of the hand-lever 28—is completed to disengage said pawl 42. When the forward stroke of the hand-lever 28 and locking-lever 58 is completed—simultaneously operating the shaft 22 and article discharging mechanism to deliver an article—the parts are returned to normal position automatically by spring 41 pulling on arm 39^a keyed to the shaft, the return or rearward movement of the locking-lever swinging dog 53 downward in the coin passage 54 until the laterally projecting rib 53^a thereon is en-

gaged by the trip-lever 64 and its lower end engages the notch 55, meanwhile the upper end of said locking-lever has lifted the outer end of the spring-actuated catch 62 and is engaged thereby so that the parts of the coin-controlled mechanism are then in the normal position shown in Fig. 4.

I claim:—

1. In a vending machine, the combination with an oscillating-rotary shaft for operating the article-discharging mechanism, of coin-controlled mechanism cooperating with said shaft and comprising a locking-lever connected thereto, a catch engaging the locking-lever, a pivoted dog carried by said locking-lever and actuated by the coin, and means operated by the dog for moving the catch out of engagement with the locking-lever. 75 80

2. In a vending machine, the combination with an oscillating-rotary shaft for operating the article-discharging mechanism, of coin-controlled mechanism cooperating with said shaft and comprising a locking-lever connected thereto, a catch engaging the locking-lever at the end of its movement in one direction, a pivoted dog carried by said locking-lever and actuated by the coin, and a trip-lever interposed between the dog and catch for moving the latter out of engagement with the locking-lever. 90 95

3. In a vending machine the combination with an oscillating-rotary shaft for operating the article-discharging mechanism, of coin-controlled mechanism cooperating with said shaft and comprising a locking-lever connected thereto, a pivoted catch engaging the locking-lever at the end of its movement in one direction and having a tail-piece by which it is moved out of engagement with said locking-lever, a pivoted dog carried by the locking-lever and actuated by the coin, and a tripping-lever operated by the pivoted dog and engaging the tail-piece of the catch to release the latter from the locking-lever. 100 105 110

4. In a vending machine, the combination with an oscillating-rotary shaft for operating the article-discharging mechanism, of coin-controlled mechanism cooperating with said shaft and comprising a locking-lever connected thereto and mounted on a supporting-plate having a vertical coin-passage, a pivoted dog suspended from the locking-lever in the coin-passage and adapted to be moved by the coin as it passes through the coin-passage, a catch pivoted to the supporting-plate and positioned to engage the locking-lever in normal position of the latter, said catch having a projecting tail-piece by which it is operated, and a trip-lever operated by the movement of the pivoted dog and engaging the tail-piece of the catch to release said catch from the locking-lever. 115 120 125

5. In a vending machine, the combination

- with an oscillating-rotary shaft for operating the article-discharging mechanism, of coin-controlled mechanism cooperating with said shaft and comprising a locking-lever connected thereto and mounted on a supporting-plate having a vertical coin-passage with a pocket at one side of the same to receive the coin and a curved slot through the front of said supporting-plate communicating with the coin-passage, said curved slot terminating at its lower end in the form of a notch, a dog pivoted to and suspended from the locking-lever within the coin-passage for operation by the coin and having an outwardly-projecting rib rounded at its lower end to engage in the notch with oppositely curved surfaces at its rear edge, said rib projecting through the aforesaid curved slot in the supporting-plate, a catch engaging the locking-lever, and means interposed between the rear edge of the rib on the dog and said catch for releasing the latter by movement of the pivoted dog.
6. In a vending machine, the combination with an oscillating-rotary shaft for operating the article-discharging mechanism, of coin-controlled mechanism cooperating with said shaft comprising a locking-lever connected thereto and mounted on a supporting-plate having a vertical coin-passage with an arc-shaped pocket in one side thereof to receive the coin and a curved slot through the front of said plate communicating with the coin-passage, said curved slot terminating at its lower end in the form of a notch, a dog pivoted to and suspended from the locking-lever within the coin-passage for operation by the coin as it enters the coin-pocket and having an outwardly-projecting rib rounded at its lower end to engage in the notch, said rib projecting through the aforesaid curved slot, a catch engaging the locking-lever, and a trip-lever interposed between the pivoted dog and catch and operated by the rib on said dog to release the catch.
7. In a vending machine, the combination with an oscillating-rotary shaft for operating the article-discharging mechanism, of coin-controlled mechanism cooperating with said shaft comprising a locking-lever connected thereto and mounted on a supporting-plate having a vertical coin-passage with an arc-shaped pocket in one side thereof to receive the coin and a curved slot through the front of said plate communicating with the coin-passage, a swinging-dog pivoted to and suspended from the locking-lever within the coin-passage for operating by the coin as it enters the coin-pocket and having a rib projecting through the aforesaid curved slot, a catch engaging the locking-lever, and a tripping-lever operated by the rib on the swinging-dog and engaging the catch to release the same from the locking-lever.
8. In a vending machine, the combination with an oscillating-rotary shaft for operating the article-discharging mechanism, of coin-controlled mechanism cooperating with said shaft comprising a locking-lever connected thereto, a catch engaging the locking-lever, a pivoted dog carried by said locking-lever and actuated by the coin, and means operated by the dog for moving the catch out of engagement with the locking-lever to permit the shaft to be turned for operating the article-discharging mechanism, together with a ratchet-wheel secured to the shaft, spaced apart pawls engaging the ratchet-wheel alternately during the opposite movements of the shaft, a tappet-member operating the pawls, and pins on the ratchet-wheel for moving the tappet-member at the end of the opposite movements of the operating shaft, whereby when the locking-lever is released a continuous movement of the same in opposite directions is assured.

DAVID H. BEELMAN.
